DAVID C. KLAUSMEYER, OF CINCINNATI, OHIO, ASSIGNOR TO THE CINCINNATI BICKFORD TOOL COMPANY, OF OAKLEY, CINCINNATI, OHIO, A CORPORATION OF OHIO.

BOX TABLE.

1,420,321.

Specification of Letters Patent. Patented June 20, 1922.

Application filed March 12, 1921. Serial No. 451,872.

To all whom it may concern:

Be it known that I, DAVID C. KLAUSMEYER, a citizen of the United States, and residing at Cincinnati, in the county of 5 Hamilton and State of Ohio, have invented a new and Improved Box Table, of which the following specification is a full disclosure.

This invention is concerned with the 10 structure of cast-metal work-supports of the so-called "box-table" type and it proposes a formation contributing towards greater economies and superior products in the manufacture thereof.

15 The routine production of satisfactory box-tables of the conventional formation is attended with noteworthy losses by reason of the difficulties encountered in obtaining a reasonably homogeneous casting, free from 20 blow-holes, pockets, or dirty metal. In the casting operation, the dross and gases, being lighter than the metal, tend to rise upwardly through the molten metal and flow towards and accumulate in the uppermost 25 portions of such molten metal, and appropriate provision is made in foundry-practice to take care of such uppermost collections of dross-metal.

Box-tables have, in accordance with conventional practice, long been made with a 30 hollow working-surface of greater area than the horizontal section of the column-like base which is cast integrally therewith. The working-surface, therefore, habitually extends 35 cornice-like beyond the base-area, and often is provided with an apron depending from one or all of the four outermost edges of the rectangular work-supporting surface. The surface of the horizontal work-supporting surface, as well as that of the exposed 40 vertical face of the apron, is provided with a series of suitable T-slots for use in clamping the blank in place.

The various walls and webs of such prior 45 box-tables were provided with ribs on their unexposed faces and the walls and webs were arranged in different ways in the interior of the structure, and reinforced also in various ways, but with the result that 50 the structures were not entirely compatible with conditions appropriate for an efficient and effective casting-operation. Consequently, flaws would frequently develop in the finished product, thereby making it

necessary to discard numbers of the cast- 55 ings; sometimes even after they had been more or less machined.

The objective of this invention is to eliminate the above-mentioned defects and losses by rendering available a box-table interiorly so arranged structurally as to prohibit the pocketing of dross or gases during the casting-operation while, at the same time, attaining a work-support of great 60 65 rigidity presenting horizontal and vertical clamping-surfaces conveniently related and arranged; all without involving an undue amount of metal and without resorting to involved patterns and cores or necessitating irksome internal reinforcements.

70 The nature of a structure typically embodying this invention may be best grasped by referring to the accompanying drawings, in which:

Fig. 1 shows a vertical section of the table, 75 the table being shown in perspective part in full lines and part dotted. Fig. 2 is a front elevation of the table. Fig. 3 is a side elevation thereof. Fig. 4 is a section of Fig. 3 on the line 4—4. Fig. 5 shows 80 a modification of the table shown in Figs. 1 to 4, inclusive, a vertical section of the perspective view of the table being shown similar to that shown in Fig. 1. Fig. 6 is a front elevation of the modification. Fig. 7 85 is a side elevation, and Fig. 8 is a section of Fig. 7 on the line 8—8.

Referring to Sheet 1 of the drawings, it will be seen that this box-table comprehends a top-wall E which, in general, is relatively 90 thin and which is interiorly corrugated, as indicated at F', to provide for suitable T-slots G sunk in the surface C of the top-platen; said ribs running longitudinally. At its one longitudinal edge, it will be noted 95 that this top-wall extends downwardly, as indicated by U, more or less according to conventional practise in drill-tables, (being corrugated like the top-wall) and that, at its lowermost longitudinal edge, it is deflected 100 inwardly and then continued downwardly as a side-wall A of the box-like hollow column which serves as a base, proper, for the table. The superficial vertical face of the upper portion of this wall is provided 105 with T-slots G and finished to form a vertical platen D. At the aforesaid point of inward deflec-

tion, it is to be noted that there are no interior right-angled corners but that the inner surface follows the contour of a gentle slope such as the ogee curve indicated by H. 5 This not only provides a junction of greater strength than a right-angled corner but it also serves the important purpose of avoiding the formation of casting defects at this point by permitting the dross and 10 gases in the fluid metal to flow upwardly as indicated by arrow J; the table being cast when in inverted position.

The upper horizontal wall E also is deflected downwardly at the opposite edge of 15 the top-platen, as indicated at K, so as to produce the side face L which depends vertically for a short distance and then is deflected inwardly and downwardly to form the slope M and it thereafter continues in 20 a vertical direction to form the other sidewall N of the hollow columnar base. It is to be noted that the depending wall L is devoid of any flange-like form or any thin blade-like edge at the point O and that 25 there is no external channel or moat between the wall L and the wall N, and that the wall N does not extend upwardly to connect with the top wall E independently and spaced away from the wall L, and that 30 accordingly the construction differs materially from formations heretofore devised. In consequence of the instant arrangement, there is no tendency for the wall L or its lowermost portion O to be formed of 35 spongy metal, since the dross and gases, during the casting operation will be afforded an easy avenue of escape in the path indicated by the arrow P; thereby avoiding, as a result of the absence of culs-de- 40 sac, the defective castings and at the same time avoiding the depending flange which, being free of marginal supports, were objectionable on account of their lack of 45 strength and accordingly not infrequently became broken away in places during the usage of the machine-tool.

Each end of the wall of the top-platen, as shown best by Figs. 2 and 3, likewise turns downwardly and extends vertically; 50 the vertical face being L-shaped and being bounded by the line of deflection O—R—S. This end-wall is integral both with the end of the top-wall and with the ends of the side-walls U and L and extends in a vertical plane from each and it undergoes deflection inwardly and laterally at the region R—S and inwardly and downwardly at the region O—R until the plane of the end-wall 55 11 of the box-like base is reached, as indicated by X—W and W—V; whereupon it again diverges and continues integrally in said plane to form the said end-wall. It is noteworthy that, as in the instances above described, this formation also avoids flanges 60 or end-walls having protruding or unsup-

ported edges and likewise ensures homogeneous metal in these regions inasmuch as the dross and gases may freely rise and escape past the points 12, 13 and 14, along the ogee or inclined paths indicated by 70 the arrows a and e, in Figs. 2 and 4 respectively. The end wall 11 extends to the side walls A and N and integrally connects therewith; the small horizontal area F being if desired closed by a web which may 75 be sloped if desired. The other end, being of similar formation, need not be described.

For the sake of avoiding the use of unnecessary metal, the base may provide the end-openings 1 and 2 and the floor-opening 80 3, and it may be provided with the lateral foot-flanges B having bolt-slots 5 and 6 for the purpose of securing the box-table to the bed of the machine tool. An internal rib 7 may be provided in the medial plane 85 of the box-table for purposes of reinforcement and an aperture C' may be provided through the top-wall E to admit the passage of the drill in certain classes of work.

In the refinement shown by Sheet 2, the 90 deflections are effected in such a manner as to provide a narrow flat surface m—n along the under-margins of the side-wall L and likewise, as indicated by r—s, as to the end-wall T. This formation is of advantage in providing a ledge affording a 95 secure seat for one leg of a clamp when it is desired to hold the work on the top-platen by means of suitable screw-clamps. This parallelism is not, however, continued 100 more than a short distance towards the column, but between the points o and n and s and x, respectively, the web is deflected 105 downwardly and inwardly in a manner similar to that already described with respect to Sheet 1.

This modified contour again eliminates the objectional casting defects by providing a natural and ready escape for the dross and gases during the casting operation; the 110 narrow flat wall provided for clamping purposes being in the path of flow and not providing a sufficient surface for the deposit of appreciable amounts of dross. Likewise, the side-lateral vertical wall 14' 115 is similarly contoured as shown by Fig. 8.

It will therefore be seen that this invention provides an integral one-piece box-table of superior strength and rigidity and of a shell-like formation avoiding depending marginal flanges or counterparts of mould culs-de-sac and hence admitting of being readily cast by means of comparatively simple cores and moulds in a manner avoiding the local formation of spongy 120 metal. Such patterns, cores and moulds being substantially counterparts or complements of the invention herein revealed, are 125 to be regarded as coordinate therewith.

I therefore claim as new and desire to 130

secure by Letters Patent the structural characteristics as follows:—

1. A one-piece shell-like box-table comprehending a hollow rectangular column having its four walls extending upwardly substantially in parallelism and then each diverging outwardly and upwardly and then again extending for a short distance in parallelism to meet a horizontal flat wall integral therewith serving as a top-platen; the interior surfaces of said box-table being free from culs-de-sac and contoured to lead progressively downwardly.

10 2. A box-table consisting of a shell-like column surmounted by a flat top-platen extended longitudinally to form closed eaves; the side-wall of the column extending upwardly and being deflected outwardly at a region somewhat below the top-platen and 15 then continuing upwardly into integral union with the top-platen to form the outermost side-wall of one of the longitudinal eaves.

3. A work-support for machine-tools consisting of a hollow column surmounted by a box-like platen extended laterally and longitudinally to form enclosed hollow eaves, the side-wall of one of said eaves being longitudinally corrugated interiorly to provide 25 external longitudinal T-slots, said side-wall being deflected in an ogee curve to integrally meet the adjacent wall of the column.

4. A one-piece table for machine-tools comprising a hollow column and an elongated flat top-wall extending horizontally beyond the base area of said column, said top-wall being deflected downwardly at its end-edges and then inwardly to form enclosed end-eaves the under-wall of which 30 integrally joins the adjacent wall of the column.

5. A one-piece work-support for machine-tools consisting of an elongated top-wall integrally downturned along its opposite longitudinal edges, one of the resultant side-walls extending vertically for a greater distance than the other and being corrugated 45 interiorly to accommodate external T-slots, each of said longitudinal side-walls being at their lowermost portions deflected inwardly and then vertically downwardly to form the adjacent wall-portions of a hollow column.

6. A one-piece shell-like box-table comprehending a hollow rectangular column having 55 its four walls extending upwardly substantially in parallelism and then each diverging outwardly and upwardly and horizontally for a short distance to form a clamp-seat and then again extending upwardly for 60 a short distance in parallelism to meet a

horizontal flat wall integral therewith serving as a top-platen; the interior surfaces of said box-table being free from culs-de-sac and contoured to lead progressively downwardly.

7. A box-table consisting of a shell-like column surmounted by a top-platen extended longitudinally to form closed eaves; the side-wall of the column extending upwardly and being deflected outwardly and for a short distance horizontally at a region somewhat below the top-platen to form a clamp-seat and then continuing upwardly into integral union with the top-platen to form the outermost side-wall of one of the longitudinal eaves.

8. A work-support for machine-tools consisting of a hollow column surmounted by a box-like platen extended laterally and longitudinally to form enclosed hollow eaves, the side-wall of one of said eaves being interiorly provided with a vertical rib and also being longitudinally corrugated interiorly to provide for external longitudinal T-slots, said side-wall being deflected inwardly for a short distance to integrally meet the adjacent upright wall of the column.

9. A one-piece table for machine-tools comprising a hollow column and an elongated top-wall extending horizontally beyond the base area of said column, said top-wall being deflected downwardly at its end-edges and then for a distance horizontally inwardly to form enclosed end-eaves the under-wall of which integrally joins the adjacent wall of the column and provides a horizontal marginal area serving as a seat for a screw-clamp.

10. A one-piece work-support for machine-tools consisting of an elongated top-wall integrally downturned along its opposite longitudinal edges, one of the resultant side-walls extending vertically for a greater distance than the other and being corrugated interiorly to accommodate external T-slots, the shorter longitudinal wall being horizontally inturned at its lower edge to form a clamp-seat, each of said longitudinal side-walls being at their lowermost portions deflected inwardly and then vertically downwardly to form the adjacent wall-portions of a hollow column.

In witness whereof, I hereunto subscribe my name, as attested by the two subscribing witnesses.

DAVID C. KLAUSMEYER.
